Kitagunma-gun (JP)

(74) Attorney, Agent, or Firm—Venable; Robert J. Frank

(**) Term: **14 Years**

(57) **CLAIM**

(21) Appl. No.: **29/137,390**

I claim the ornamental design for the housing for a blood
pressure measuring device, as shown and described.

(22) Filed: **Feb. 21, 2001**

DESCRIPTION

(30) **Foreign Application Priority Data**

FIG. 1 is a perspective view of a first embodiment of my
housing for a blood pressure measuring device including a
memory select switch;

Aug. 22, 2000 (JP) 12-023020

FIG. 2 is a top view of the first embodiment;

(51) LOC (7) Cl. **24-01**

FIG. 3 is a bottom view of the first embodiment;

(52) U.S. Cl. **D24/165**

FIG. 4 is a front view of the first embodiment;

(58) Field of Search D24/165, 167;

FIG. 5 is a rear view of the first embodiment;

600/480, 481, 485, 479, 490, 493, 494,

FIG. 6 is a right side view of the first embodiment;

495

FIG. 7 is a left side view of the first embodiment;

(56) **References Cited**

FIG. 8 is a perspective view of a second embodiment of my
invention without a memory select switch;

U.S. PATENT DOCUMENTS

FIG. 9 is a top view of the second embodiment;

D. 283,916 * 5/1986 Akiyama D24/165

FIG. 10 is a bottom view of the second embodiment;

D. 324,570 * 3/1992 Arioka et al. D24/165

FIG. 11 is a front view of the second embodiment;

D. 352,463 * 11/1994 Kubo D10/31

FIG. 12 is a rear view of the second embodiment;

D. 423,102 * 4/2000 Mertenat D24/169

FIG. 13 is a right side view of the second embodiment; and,

FIG. 14 is a left side view of the second embodiment.
